CATHODE RAY TUBE APPARATUS

Kurt Schlesinger, Berlin, Germany, assignor to
 Radioaktiengesellschaft D. S. Loewe, Berlin-
 Steglitz, Germany

Application February 9, 1935, Serial No. 5,870
 In Germany February 12, 1934

3 Claims. (Cl. 250—27)

The invention relates to oscilloscopes or television apparatus using cathode ray tubes the cathode ray of which is kept in movement by a relaxation oscillator connected to the deflecting 5 plates or coils of the tubes. It is well known that the fluorescent screen of the tube is damaged when the ray hits for a longer time the same point of the screen.

It is the object of the invention to avoid the 10 burning of the stationary cathode ray into the luminous screen by preventing that the ray is not switched on until the relaxation oscillator has already commenced to move the ray and to switch out the ray when the oscillator ceases to work.

15 This is illustrated in the accompanying drawing, in which

Fig. 1 shows a simple embodiment of the invention, whilst

20 Figs. 2 and 3 show more complicated connections according to the invention.

In Fig. 1, the relaxation condenser 3 is charged from the battery 1 having a relatively high potential (approximately 1000 volts) through the medium of a resistance 2, and is discharged 25 through the medium of a gas-filled grid-controlled tube having a hot cathode and grid. The anode of the tube is connected to an amplifier supplying the deflecting potentials respectively currents, whilst the grid, in the case of a television receiver, receives the synchronizing impulses. The maximum charging potential of the 30 condenser 3, if the hot cathode is in operation, amounts to not more than 20 to 40 volts depending on the value of the adjusted grid bias of the 35 tube 4. Until the cathode has become hot, however, the tube does not ignite until considerably higher potentials have been reached. In certain forms which operate with an extremely small pressure, for example those filled with mercury vapour, an ignition does not take place at all in the cold condition, as the requisite vapour pressure only develops as the cathode gets hot.

In the meantime, the cathode ray may already be developed and burn the screen. The 45 same happens when, by any reason, the relaxation oscillations cease before the cathode ray is switched off.

In order to overcome this danger a glow lamp 5 in series with the electromagnet 6 of a relay 50 switch 7, 8 is provided in parallel to the tube 4.

This glow lamp 5 preferably contains cold electrodes, is filled with a rare gas of proper kind and pressure and is so dimensioned that its ignition potential is higher than the anode potential of the normally operating tube 4. On

the other hand the ignition potential of the safety lamp 5 should be lower than the ignition potential of the unheated tube 4. These conditions may readily be fulfilled, for example, by filling the lamp 5 with neon of 15 mm. pressure, whilst the tube 4 is filled with argon or mercury vapour at a pressure of approximately 10^{-2} to 10^{-3} mm. The ignition potential of 5 is then of the order of 150 volts, whilst the ignition potential of 4 if filled with mercury vapour is not 10 reached by the battery 1 at all, and if filled with argon is of the order of several hundred volts. In consequence the glow lamp 5 lights first shortly after the switching on. Its terminal potential is approximately 100 volts and does not 15 surmount this normal cathode fall owing to the large surface of its electrodes. Immediately the lamp 4 has become hot, the potential on the same drops to approximately 20-40 volts, so that the glow lamp 5 is extinguished, as its quenching 20 potential is not much less than 100 volts.

The relay 6 interrupts the circuit at 7 and 8 for such time as a discharge current traverses the auxiliary glow lamp 5. In this circuit there may be connected, for example, the anode potential of 25 the television tube or the grid potential of the television tube, in such fashion that the moving image point does not appear until the contact between 7 and 8 has been closed. In this way the television tube, even if the same has a shorter 30 heating period than the connected tilting apparatus, is prevented from burning the screen with a stationary spot of light.

This method of mechanically switching on may be replaced by an electrical method principally 35 making use of safety glow lamps the particular dimensions being adapted to the special purpose.

Two forms of embodiment of such an arrangement according to the invention are illustrated 40 by way of example in Figs. 2 and 3.

In Fig. 2, the line and frame relaxation oscillators of a television receiver are, according to Fig. 1, marked with 2, 3, 4 and 2', 3', 4'. The tubes 4 and 4' are shunted by glow lamps 5 and 5', which are, instead to a relay, connected to a 45 common resistance 6. They accordingly produce at this resistance 6 a bias, which is positive against earth, up to the moment when the tubes 4 and 4' have become hot and the glow lamps 5 and 5', therefore are extinguished. The high 50 tension supply apparatus of the television tube, which includes the one-way rectifier tube 16 the condensers 9 and 10 and the steadyng resistance 11, is coupled galvanically with this resistance 6 through the medium of a resistance 12. The 55

cathode 13 of the television tube is connected with the point 14, its control grid 15 with the cathode of the tube. The bias is adjusted finely by the potentiometer tapping 17.

5 The operation of the arrangement is as follows: so long as the glow lamps 5 and 5' are burning, i. e., the tilting apparatus is not in operation, the cathode 13 is positively biased against the control grid 15 of the television tube, which grid 10 remains negative. This bias is certainly but a fraction of the potential at 6, but the latter may be selected in such amount that the bias suffices to keep the image field dark. Thus, for example, the resistance 12 may be selected at 10^6 ohms and 15 the potentiometer 11 at $.3 \times 10^6$ ohms. Of the latter merely one-tenth is required for adjusting the bias of 15. There accordingly then occurs at the cathode 13 exactly one-quarter of the bias of the resistance 6 against the control grid 15. If the 20 resistance 6 is selected at 100,000 ohms, there is readily obtained at the same a bias of 100 volts, as the feeding of the relaxation apparatus with the potential 18 takes place with a potential of approximately 1,000 volts. There is accordingly 25 obtained a blocking potential of 25 volts, which is fully sufficient to darken the television tube. Immediately the tubes 5 and 5' are extinguished, the potential at 6 collapses automatically, and the television tube is released.

30 Another form of embodiment of the invention is shown in Fig. 3. In this there is employed a special glow lamp 19. The lamp has two anodes 20, 20', which are connected with the relaxation condensers. It also possesses a cathode 21 and 35 a third electrode 22. Now the conditions of discharge are so unfavourable between this third electrode and the cathode 21 that the discharge is not initiated upon full operating potential of the television tube. This may be obtained in 40 several known ways, for example by placing the auxiliary cathode 22 so that it extends into the dark space in front of the cathode 21. On the other hand the anodes 20, 20', ignite against the cathode 21 as soon as the apparatus is switched 45 on. Immediately this discharge has commenced, which ensures that the relaxation condensers cannot be charged higher, the anode rays pass through the tubular cathode 21, and causes electrons to be emitted from the auxiliary cathode 22, which 50 produce a discharge between 21 and 22. By reason of the resistance 23 according to the invention the cathode 13 of the television tube is then raised to an abnormally high positive potential in relation to the control grid 15 of the same ray, 55 so that the tube is blocked. Immediately the tubes 4 and 4' have become hot the discharges between 20, 20' and 21 cease, and in this way the discharge between 22 and 21 is also caused to disappear. The television tube is thus able to 60 perform emission. The resistance 23 is so chosen that no appreciable drop in potential takes place

at the same during the operation of the television tube. With the usual emissions of approximately 500 microamperes for the television tube the glow lamp 19 is so calculated that a current of a few milliamperes flows through the glow lamp. The 5 resistance 23 is then of the order of several times 10,000 ohms. It is bridged by a condenser 24, which amounts to approximately 1 mf., and passes emission peaks in the television tube occurring during the normal operation. 10

I claim:

1. In a relaxation oscillation circuit comprising a direct current source, a grid-controlled gas-filled thermionic tube, a condenser and a charging resistance, a safety device consisting of a glow-discharge lamp in series with a relay, both in parallel to said tube, the igniting potential of said lamp being higher than the anode potential of the normally operating tube. 15

2. In a cathode ray tube system comprising a 20 cathode ray tube having cathode, control grid and anode, a direct current source and two relaxation oscillators according to claim 1, and a high-voltage direct current source connected to cathode and control grid of said cathode ray 25 tube, a safety device for suppressing the cathode ray as long as said relaxation oscillators are not working, said device consisting of two glow discharge lamps, each connected to the anode of one of said thermionic tubes, and their common 30 second terminal connected to an earthed resistance, said common terminal connected by a high resistance to the cathode of said cathode ray tube, the control grid of said cathode ray tube being connected to said high voltage source at a 35 point more negative than said cathode.

3. In a cathode ray tube system comprising a cathode ray tube having cathode, control grid and anode, a direct current source and two relaxation oscillators according to claim 1, and a high 40 voltage direct current source connected to said cathode and control grid of said cathode ray tube, the positive terminal of said high voltage source being earthed, a safety device for suppressing the cathode ray as long as said relaxation oscillators are not working, said device consisting of a glow discharge lamp having four electrodes, one of said electrodes connected to the anode of one of said thermionic tubes, another of said electrodes connected to the anode of the other of 45 said thermionic tubes, a third electrode connected to earth, and the fourth electrode connected to the cathode of said cathode ray tube, a resistance having one terminal connected to the cathode of 50 said cathode ray tube and another terminal connected to said high voltage source, and a condenser shunted across said resistance, the control grid of said cathode ray tube being connected to said high voltage source at a point 55 more negative than said cathode.

KURT SCHLESINGER.
